UNITED STATES PATENT OFFICE.

EDGAR SCOFIELD, OF NEW YORK, N. Y., ASSIGNOR TO ANCHOR CAP AND CLOSURE CORPORATION, OF LONG ISLAND CITY, NEW YORK, A CORPORATION OF NEW YORK.

CLOSURE CAP AND PACKAGE.

Application filed March 27, 1925. Serial No. 18,674.

This invention relates to the art of packaging and particularly to a closure cap and to a package.

The principal object of the invention is to provide an inexpensive effective closure adapted to close a plurality of types of containers.

A more specific object of the invention is to provide a closure cap adapted to close a container having either a screw lug finish or a snap-on finish.

Another object of the invention is to provide a closure cap locking projection which is adapted to act either as a screw lug or as a friction button.

Other objects of the invention will be apparent from the following description taken in connection with the accompanying drawings.

The invention is disclosed in the form of a sheet metal closure cap having a cover portion and a skirt portion. At intervals about the skirt there are provided angle shaped impressed portions of metal which act as locking projections. Each of these locking projections consists of an arm which extends circumferentially of the skirt and a second arm which extends substantially vertically of the skirt.

This closure is adapted to be applied either to a container provided with projecting screw lugs or to a container provided with a friction sealing zone which may diminish in diameter from top to bottom where it is engaged by projections on the cap. When the cap is applied to the first type of container, the circumferentially extending arms of the cap lugs engage the underneath side of the container lugs and act as screw threads. The vertical arms of the cap lugs act as detents to arrest rotation of the cap when it has been completely screwed on the container. When the cap is applied to a container provided with a friction finish or the like, the locking projections of the cap act as friction buttons which cooperate with the finish of the container.

Fig. 1 of the drawings is an elevational view partially in section showing a closure cap embodying the present invention.

Fig. 2 is a fragmentary elevational view partially in section illustrating a container having a screw lug finish which is adapted to receive the cap shown in Fig. 1.

Fig. 3 is a fragmentary sectional view showing the closure of Fig. 1 applied to a container having a so-called friction or snap-on finish.

Fig. 4 is an elevational view showing a shallow flange cap embodying the present invention.

Fig. 5 is a fragmentary elevational view showing a screw lug finish container adapted to receive the closure shown in Fig. 4.

The closure cap comprises a cover portion 1, which may have a depressed center, and a skirt 2 which may be corrugated as at 3 for the purpose of greater stiffness. Near the bottom of the skirt locking projections 4 are positioned at suitable intervals about the circumference of the skirt. As shown, these locking projections may be formed by metal pushed inwardly from the skirt. Each of these projections is of angular form and comprises a substantially horizontal arm 5, which extends circumferentially of the skirt, and a substantially vertical arm 6, which is approximately perpendicular to the arm 5 at its end. As shown in Fig. 1, the upper surface of the arm 5 is inclined downwardly to form the operative surface of a screw thread; and as shown in Figs. 1 and 3, the vertical arm 6 preferably so varies in depth that the inner surface of this arm tapers outwardly radially of the cap.

The cap is applied to a container of the type shown in Fig. 2 by passing the locking projections 4 down between the container lugs 7 and then rotating the cap in a clockwise direction, looking down upon the container. The upper surfaces of the arms 5 engage the under surfaces of the lugs 7 and lock the cap on the container. When the cap has been fully screwed on, the vertical arms 6 engage the edges of the lugs 7, thereby acting as detents which arrest rotation of the cap. To form a hermetic seal the cap may be provided with a suitable gasket 10.

The container shown in Fig. 3 is provided with a curved finish, which has its maximum

diameter at the center 9. Beneath the center portion 9, the finish curves inwardly and forms a cap engaging zone diminishing in diameter from top to bottom of the zone. 5 The cap is applied to the container of Fig. 3 by pushing it directly down over the finish. As the lugs 4 approach the center portion 9 of the finish they are pushed outwardly, while intermediate the lugs the skirt flexes inwardly. As soon as lugs 4 have passed the center of the finish the resiliency of the skirt causes it to spring into its original shape, thereby moving the lugs 4 inwardly with the result that the cap snaps into place 10 upon the container. As shown in Fig. 3, the tapering inner surface of the vertical arm 6 conforms to the shape of the finish of the container; and this surface, together with the operative surface of the horizontal arm 20 5, causes the lug to act as a so-called friction button, which holds the cap in place upon the container.

The present invention is adapted to either a deep flange cap, as shown in Fig. 1, or a shallow flange cap, as shown in Fig. 4; and the cap may be formed with a plain edge, as shown in Fig. 1; or with a suitable wire edge, as shown in Fig. 4.

It is seen that the present invention provides a simple inexpensive type of cap which, in addition to other advantageous features, has the characteristic that it is adapted for sealing either containers with a screw lug finish or containers with a friction type of finish.

Having thus described my invention, what I claim is:

1. In a closure cap; a skirt having a locking projection comprising an arm extending circumferentially of the skirt, the upper surface of said arm being inclined to act as a section of a screw thread in the application of the closure to a suitable container; and a detent extending upwardly at one end of 45 said arm, said detent being formed of metal pressed inwardly from the body of the skirt.

2. In a closure cap; a skirt having a locking projection comprising a horizontal portion and an upwardly extending impressed 50 portion, said upwardly extending portion having an inner surface which tapers outwardly radially of the cap to conform with the taper of a friction zone on a container.

3. In a closure cap; a skirt having a locking projection comprising an arm extending circumferentially of the skirt and an arm extending substantially vertically of the skirt, the upper surface of the first arm being inclined downwardly from the vertical arm 60 to form a section of a screw thread and the inner surface of the vertical arm tapering radially outward from bottom to top thereof.

4. In a closure cap, a skirt having an angularly shaped locking projection adapted 65 to act as a screw lug in the application of

the closure to a screw container and as a friction button when the closure is applied to a friction type of container.

5. A package comprising a container having a cap engaging zone diminishing in diameter from top to bottom; in combination with a cap comprising a skirt embracing said zone, said skirt having a friction button consisting of a horizontal arm engaging said zone and a tapering vertical arm likewise engaging said zone. 70

6. A package comprising a container having a cap engaging zone diminishing in diameter from top to bottom; in combination with a cap comprising a skirt embracing said zone, said skirt having horizontal and vertical impressed portions engaging said zone and said vertical impressed portion varying in depth to conform to the shape of said zone. 80

7. In a closure cap, a cylindrical sheet metal skirt comprising a plurality of inwardly pressed projections each of which comprises a vertically extending arm and a circumferentially extending arm inclined 90 downwardly from said vertically extending arm, the end of said circumferentially extending arm joining the end of said vertically extending arm, resilient springy sheet metal portions between said projections, and 95 an annular corrugated zone above said projections.

8. In a closure cap; a cylindrical sheet metal skirt comprising a plurality of inwardly pressed projections, each of which comprises a vertically extending arm and a circumferentially extending arm inclined 100 downwardly from said vertically extending arm, the inner surface of said vertically extending arm being tapered outwardly from 105 bottom to top; resilient springy sheet metal portions between said projections; and an annular corrugated zone above said projections.

9. In a closure cap; a long cylindrical 110 sheet metal skirt comprising a plurality of inwardly pressed projections positioned at a considerable distance below the top of the cap, each of said projections comprising a horizontal arm and a vertical arm joined 115 end to end; and resilient springy sheet metal portions between said projections.

10. A package comprising a container having a finish rounded in a vertical and horizontal direction adjacent its mouth; in combination with a closure having a cylindrical sheet metal skirt comprising a plurality of inwardly pressed projections each of which has a vertically extending arm and a circumferentially extending arm; and resilient springy sheet metal portions between said projections, said projections being held 120 in cooperative relationship with the finish of said container by the resiliency of said portions. 125

11. A package comprising a container having a finish adjacent the mouth adapted to cooperate with projections on the skirt of a cap; in combination with a cap having a skirt embracing said finish, said skirt having a series of projections, each of which comprises a substantially vertically extend-

ing arm with its end joined to a circumferentially extending arm inclined downwardly from the vertical arm, each of the arms 10 cooperating with the finish of the container when the cap is in place thereon.

EDGAR SCOFIELD.
